MEANS FOR FILING MICRO-SLIDES

Edwin C. Weiskopf, New York, N. Y.

Application August 14, 1937, Serial No. 159,066

1 Claim. (Cl. 45-2)

The present invention relates to filing means such as filing cabinets, and more particularly to means for filing a multiplicity of slides, such as those utilized in connection with microscopes usually for biological and bacteriological investigations. For convenience in reference slides of this character will hereafter be referred to as "micro-slides".

The primary object of the invention is the provision of means for the filing of micro-slides of various sizes at low cost and with a high degree of flexibility in the sense that a single cabinet may be readily adapted to the filing of a variable large number of slides of different sizes without alteration of the cabinet itself. Thus, for example, in a cabinet provided with compartments of uniform size and with drawers of uniform size, it is possible in accordance with the present invention to file in such drawers, without altering the construction of the latter, a multiplicity of micro-slides arranged in groups in a visible filing system. Further, any drawer of the cabinet may be used without alteration for storing in large numbers a multiplicity of the slides. Also such drawers may be used interchangeably for filing index cards and lantern slides.

It is also an object of the present invention to provide a cabinet of the class described with means for the filing of flat filing trays constructed and arranged to hold a plurality of slides in sub-compartments provided in such trays.

A yet further object of the invention is generally to provide means for economically filing a maximum number of slides in a minimum space while at the same time providing for the visible filing of a multiplicity of slides as well as for storage filing and flat filing of such slides.

The above objects of the invention and other objects ancillary thereto will be fully understood from the following description considered with reference to the accompanying drawings which illustrate the preferred embodiment of the invention.

In the drawings:

Fig. 1 is a perspective view of a filing cabinet embodying the present invention, one of the drawers and one of the filing trays being shown in partially withdrawn position;

Fig. 2 is a side view, partly in elevation, of one of the drawers and of one of the inserts positioned in said drawer, with parts broken away for the sake of clearness of the illustration;

Fig. 3 is a perspective view of an insert for micro-slides of a predetermined size, say $3'' \times 2''$;

Fig. 4 is a fragmentary top plan view of an in-

sert for micro-slides of a different size, say $3'' \times 1\frac{1}{2}''$;

Fig. 5 is a view similar to Fig. 4 of an insert for micro-slides of two different sizes, say $3'' \times 1\frac{1}{2}''$ and $3'' \times 1''$, respectively;

Fig. 6 is a fragmentary top plan view of an insert for lantern slides;

Fig. 7 is a top plan view of an insert for the storage filing of a multiplicity of slides of different sizes;

Fig. 8 is a sectional view on the line 8-8 of Fig. 7;

Fig. 9 is a fragmentary top plan view of a flat filing tray;

Fig. 10 is a detailed sectional view on the line 10-10 of Fig. 9.

Referring now more particularly to the drawings, the filing cabinet 10 embodying the present invention comprises a base 12, a plurality of drawer sections 14, a section 16 having compartments 20 for the flat filing trays and a top section 18. The cabinet is thus of sectional construction and may comprise a larger or smaller number of sections than here shown, said sections being readily assembled in relation to each other and the base 12 and top 18. Preferably, said sections are made of sheet metal.

Each drawer section 14 comprises a plurality of compartments, such as that indicated by the reference numeral 20, of uniform size in which compartments sheet metal drawers 22 are slidably mounted. Said drawers 22 are of uniform size for interchangeable mounting in the compartments formed in the metal frame of the cabinet.

An important feature of the present invention is the provision of means for filing in drawers 22 a multiplicity of micro- and other slides of different sizes as for example, $3'' \times 1''$, $3'' \times 1\frac{1}{2}''$ and $3'' \times 2''$ in such manner that any of such slides may be filed in any of said drawers, either in a visible filing system or in a non-visible manner as, for example, in the storage filing of slides. For this purpose, there is provided a plurality of inserts each having the same or substantially the same overall dimension whereby to fit interchangeably any of drawers 22 but otherwise constructed and arranged for the filing therein of a plurality of slides of predetermined size or sizes. As illustrated in Figs. 2 and 3, an insert 24 for $3'' \times 2''$ slides is removably positioned within drawer 22. Similar inserts 26, 28 and 30, shown in Figs. 4, 5 and 6, respectively, each have the same overall dimensions as insert 24 whereby any of said inserts may be positioned in drawer 22.

in lieu of insert 24. As here shown, insert 26 is provided for the filing of 3" x 1½" slides, while insert 28 is provided for the filing in separate groups of 3" x 1½" and 3" x 1" slides respectively, and insert 30 is provided for the filing of lantern slides. Said inserts are preferably made of wood and in the case of the micro-slide inserts they are provided with sub-compartments. Thus, for example, insert 24, as here shown, has two sub-compartments 32 formed by a central partition wall 34 extending longitudinally of said insert midway between the two side walls thereof. Said intermediate partition wall and said side walls are provided with closely spaced slide receiving grooves 36. As shown in Fig. 3, said grooves extend for the full height of said walls whereby said slides are supported edgewise on the bottom 38 of the insert. Said grooves may be dimensioned to receive but a single slide, but are preferably wide enough to receive two slides S in back to back relation, as illustrated in Fig. 2.

Inserts 26 and 28 are similarly constructed with intermediate or partition walls 40 and 42, respectively, extending for the full length of said inserts for forming in the latter sub-compartments 44 and 46 and 48, respectively, sub-compartments 44 and 46 in inserts 26 and 28 being provided for 3" x 1½" slides and sub-compartments 48 in insert 28 being provided for 3" x 1" slides. Said inserts are provided with grooves 49 in their partition and side walls, as shown, for receiving the slides, it being understood that except for the number of sub-compartments, inserts 26 and 28 are of the same construction as insert 24. Referring to Fig. 6, it will be observed that insert 30 is provided with grooves 50 for receiving lantern slides. Said grooves are provided in the side walls 52 of said insert and extend for the full height of said walls whereby the slides are supported edgewise on the bottom 54 of insert 30. Thus, it will be apparent that micro- and other slides of various sizes may be filed in a visible filing system in any drawer 22 by providing said drawer with a suitable insert such as one of those which have just been described.

In accordance with the present invention, provision is made for the storage filing of a large number of slides of any of the sizes which may be filed in a visible filing system, as hereinbefore described. For this purpose, an insert 56, such as that illustrated in Figs. 7 and 8 is provided. Insert 56, which is preferably made of wood, has the same or substantially the same overall dimension as any of the above mentioned inserts and is thereby adapted to be removably positioned in any one of drawers 22 in interchangeable relation with the above mentioned inserts. As here shown, end walls 58 of insert 56 is provided with a plurality of spaced grooves 60 in which the end portions of partition walls 62 are removably received. Partition walls 62 may be formed of wood or of any other suitable material, such as fibre-board. When formed of fibre-board, said walls may be somewhat flexible and in that event, in order to maintain said walls against lateral flexing, grooves 64 are provided in the bottom 66 of insert 56, the bottom edges of the inserts being received in said grooves. It will be observed that partition walls 62 may be positioned in proper spaced relation whereby to define sub-compartments 68 which may vary in width, respectively, for receiving slides of different sizes. As illustrated, the slides S may be mounted in said compartments in close face to

face relation whereby a large number of said slides may be stored in said insert.

Referring now more particularly to Figs. 1, 9 and 10 of the drawings, it will be noticed that provision is made for the filing of slides in flat filing trays 70 constructed and arranged for positioning the slides in horizontal position. For this purpose, section 16 is provided with a plurality of compartments 72 of uniform size, trays 70 being slidably and removably mounted in said compartments 72. Said section is provided with a cover-door 74 hinged at its lower edge in the front opening of the frame 16 whereby said door is movable outwardly and downwardly to permit the insertion and removal of trays 70 from compartments 72. Tray 70 is made of sheet metal and as here shown comprises a bottom 76, side walls 78, a front end wall 80 and a rear end wall 82. Spaced vertically disposed partition members 84 are struck up from the bottom 76 of the tray to define sub-compartments 86 for the slides, and a hole 88 is provided through the bottom 76 at each of said compartments for the insertion of a finger to facilitate removal of the slides from the spaced compartments. Partition members 84 are preferably high enough to permit the filing in each compartment of at least two micro-slides, it being understood that said slides will be mounted in said sub-compartments in face to face relation and supported in horizontal position on bottom 76. The front edge 80 of the tray is provided with a downwardly and outwardly reflexed portion 90 providing a hand grip to facilitate the sliding of the tray into and out of its compartment in the frame of section 16. Said portion 90 is provided with a flange 92 which together with a similar flange 94 on a plate 96 defines an index-plate receiving groove. Plate 96 may be secured to portion 90 in any suitable manner as by welding or riveting.

Thus it is seen that the construction herein shown and described is well adapted to accomplish the several objects of the present invention. It will be understood, however, that while I have shown and described the preferred embodiment of my invention, the latter may be embodied otherwise than as here shown and that in the illustrated embodiment, certain changes and omissions may be made within the spirit of the invention. Therefore, I do not wish to be limited precisely to the construction herein specifically disclosed, except as may be required by the appended claim considered with reference to the prior art.

Having thus described my invention, what I claim and desire to secure by Letters Patent is:

A cabinet of the class described for filing a multiplicity of micro-slides of different sizes in groups containing slides of the same size, said cabinet comprising a frame having a plurality of compartments of uniform sizes, a plurality of drawers of uniform size slidably and removably mounted in said compartments, and an insert removably positioned interchangeably in each of said drawers and having sub-compartments for the filing therein of groups of slides of different sizes, respectively, said insert having a plurality of spaced longitudinally extending walls arranged in pairs and thereby defining said sub-compartments in said insert, the walls of one pair being more widely spaced than the walls of another whereby the sub-compartments are of different widths, each of said walls having a multiplicity of closely spaced open top grooves which are in alignment and confront each other in each

of said sub-compartments providing companion slide receiving grooves, each of said grooves being of such width as to receive two slides and to hold the same in vertical face to face contact, with the slides in companion grooves spaced from the slides in adjacent companion grooves of the same sub-compartment, said sub-compartments

of different widths being thus constructed and arranged to have visibly filed therein a large number of slides of different sizes, each of said inserts having front and rear walls, and each of said drawers having front and rear walls which 5 extend above said insert walls.

EDWIN C. WEISKOPF.
